UNITED STATES PATENT OFFICE.

WILLIAM E. NICKERSON, OF CAMBRIDGE, AND ADOLPH BERRENBERG, OF SOMERVILLE, MASSACHUSETTS, ASSIGNORS TO THE BEACON VACUUM PUMP AND ELECTRICAL COMPANY, OF PORTLAND, MAINE.

VACUUM-PUMP.

SPECIFICATION forming part of Letters Patent No. 453,277, dated June 2, 1891.

Application filed June 20, 1890. Serial No. 356,104. (No model.)

To all whom it may concern:

Be it known that we, WILLIAM E. NICKERSON, of Cambridge, and ADOLPH BERRENBERG, of Somerville, both in the county of 5 Middlesex and State of Massachusetts, have invented new and useful Improvements in Vacuum-Pumps, of which the following, taken in connection with the accompanying drawings, is a specification.

10 The object of this invention is to so construct and arrange a vacuum-pump that the flow of air from the article being exhausted shall be continuous and without abrupt pulsations, and that the use of valves, pistons, and joints may be avoided. The mechanical device, taken in connection with a sealing-liquid, constitutes the invention, which may be understood by reference to the accompanying drawings, in which—

15 Figure 1 is a front elevation of the device, the front of the outside casing being represented as removed so that the interior construction and arrangement may be more clearly shown. Fig. 2 is an end elevation and 20 section of parts of the device. Fig. 3 shows a part of the same in plan. Fig. 4 represents one of the elastic pipes collapsed at intervals. Fig. 5 is a cross-section of one of the pipes. Fig. 6 is a cross-section of one of the pipes 25 collapsed.

In the drawings, A represents the base of the pump, and B a case, which, together with the base A, forms a tank or receiver in which the pump proper is inclosed.

30 The main shaft D of the pump is mounted in housings H H, Fig. 1. For sealing the shaft D as it passes through the case B, a pocket B' is formed on the outside of the case, so that the packing-box D³ may be covered with a 35 sealing-liquid, as indicated in Fig. 1.

D² represents a packing-box formed in the wall of the pocket, and serves to make the joint around the shaft D tight.

D' is a driving-pulley.

40 Upon the main shaft D two six-armed spiders C C are placed and securely fastened. Long rolls E are journaled in the arms of the spiders, as shown. These rolls E have annular grooves e e in them, dividing them into 45 divisions e' e', and each roll is provided with

a gear E' at one end. The gears E' engage with an internal gear E², the whole device being so constructed that when the main shaft D rotates the rolls E revolve about the center of the shaft D, and at the same time 55 each is made to rotate on its own center with a determined rate of speed controlled by the internal gear E², said internal gear E² being rigidly attached to the base A by bolts or otherwise. Each division e' e' traverses in a 60 groove A', made in the base A. The walls of these grooves are shown at a a, Fig. 1. Elastic pipes R R are placed one in each of the grooves A'. The divisions e' e' of the rolls E E are so adjusted as to collapse the pipes 65 R by pressing upon them as they lie in the grooves A'. (See Fig. 2.) The pipes R are each united to a hollow shaft R' and through it to a short pipe R³, extending laterally from the pipe R⁴. The hollow shafts R' are each 70 provided with a gear R², so that they may be made to rotate slowly. These shafts R' fit closely into the short pipes R³ and are free to turn with the gears. The gears R² are rotated by the following-described device.

K is a bent lever pivoted at K' to the base, and is operated by the cam D⁴ (see Fig. 2) and spring S. At the lower end of the bent lever K a pawl K² is attached. This pawl K² engages with the teeth of the gear K³ and causes 75 it and through it all of the gears R² R² to slowly rotate, their motion being intermittent. As the elastic pipes R R are each indirectly connected with one of these gears R² it is evident that they must also rotate.

The operation of this device is as follows: Oil or some other suitable sealing-fluid is admitted to each of the pipes R R through openings located at some convenient point, as at T, Fig. 2. Now as the rolls E pass over 90 the pipes in the grooves A' in the base A the pipes are collapsed, as indicated, and as the collapsing action advances it is evident that a vacuum is formed behind the point at which the pipe is just collapsed, and that as the 95 rolls E continue to advance the vacuum-forming action must continue and thus cause a flow of air into the pipe R and from the pipe R⁴, thus causing a vacuum in the pipe R' and in the article connected to it. The oil or 100

other sealing-liquid in the pipes R serves to completely seal and make air-tight the pipes at the points when they are collapsed.

The object in causing the pipes to slowly 5 rotate or twist on the axis is to prevent them from being worn out in one part more than in another.

The rolls E E rotate on their axes a little faster than they would if left free to roll on 10 the pipes R R, being impelled by the gears E' E', which engage with the fixed internal gear E², the pitch-line of the gears E' E' being less in circumference than the rolls E E, so that the peripheral motion of the rolls will 15 be more than that due to rolling on the pipes. This acceleration of the peripheral motion of the rolls prevents the forcing forward of the pipes, which if allowed to take place would place them under great longitudinal strain, 20 which would tear them apart or at least seriously injure them. This device is used, preferably, with the receiver nearly full of oil or some other suitable liquid.

In case no liquid is used in the receiver the 25 sealing-liquid for the interior of the pipes R R can be conveyed to them by tubes arranged for the purpose.

If elastic pipes having thick walls and great 30 resilience are used, full atmospheric pressure may be allowed in the receiver B; but with attenuated air in the receiver much lighter

and larger pipes can be used, as in this case the resilience of the pipes will not be opposed by the pressure of the air except to a limited extent.

35

We claim—

1. In a vacuum-pump, the combination of elastic compressible pipes and rolls having mechanism adapted to force said rolls along the pipes and collapse the same with a sealing-liquid within the pipes to completely seal them at the collapsed points, substantially as and for the purpose set forth. 40

2. In a vacuum-pump, the combination of the elastic compressible pipes and rolls E E 45 for collapsing them, operating as described, with mechanism whereby the rolls E E rotate on their axes faster than they would if left free to roll on the pipes R R, substantially as and for the purpose set forth.

3. In a vacuum-pump, the combination of elastic compressible pipes and rolls E E for collapsing them, as described, with mechanism whereby the said pipes are made to slowly rotate on their central lines, substantially as and for the purpose set forth. 50
